UNITED STATES PATENT OFFICE.

HAROLD B. CRANSHAW, OF BOSTON, MASSACHUSETTS.

RECEPTACLE.

Application filed February 21, 1918. Serial No. 218,575.

To all whom it may concern:

Be it known that I, HAROLD B. CRANSHAW, a citizen of the United States of America, and resident of Boston, in the county of 5 Suffolk and State of Massachusetts, have invented new and useful Improvements in Receptacles, of which the following is a specification.

This invention relates to receptacles and 10 more particularly to paper receptacles designed for use as sputum cups.

The principal object of the invention is to produce a flask which can be cheaply and easily constructed, which will hold rigidly 15 together after being assembled, which may be formed from a single piece of material including the cover, and which has an improved tapered or wedge-shaped locking means by which the cover may be quickly 20 opened or closed and by which the cover is held firmly closed when locked.

Other objects of the invention will be apparent from the following description and the accompanying drawings, in which—

25 Figure 1 is a plan view of the blank from which the receptacle is constructed;

Figure 2 is a front elevation of the receptacle when closed and locked;

30 Figure 3 is a vertical central longitudinal section of the receptacle on line 3—3 of Fig. 2;

Figure 4 is a vertical central transverse section of the receptacle with the cover raised;

35 Figure 5 is a front elevation of a modified receptacle showing the cover practically raised; and

Figure 6 is a front elevation of the modified receptacle of Fig. 5, showing the cover 40 closed and locked.

The particular embodiment of my invention illustrated in Figs. 1 to 4 comprises a rectangular receptacle having a bottom 1, a front 2, a back 3, sides 4 and 5, gusset corners 6, 7, 8 and 9, folding rims 10 and 11 at the front and back, folding rims 12, 13, 14 and 15 at the sides, extensions 16 and 17 at the sides having locking tabs 18 and 19, a cover 20 connecting integrally with the cup 50 by means of a neck 21, and a cover lock 22 adapted to cooperate with an opening 23, in the rim 10 to lock the cover in closed position.

As illustrated in Fig. 1 the receptacle, including the cover, is preferably formed from a single piece or blank stamped or other-

wise cut into the form shown from sheet paper, paperoid, leatheroid, or the like. In forming the receptacle the blank is folded along the dash lines into the shape shown in Figs. 2, 3 and 4. The rims 11—12—13 and 10—14—15 are first folded outwardly through 180°. The front 2, back 3, and sides 4 and 5 are then bent into an upright position. The cover gussets 6—8 and 7—9 are folded inwardly along the outside of the sides 4 and 5. The extensions 16 and 17 are folded downwardly over the rims 12—14 and 13—15 and over the folded gussets at each side and the locking tabs 18 and 19 are folded upwardly under the folded gussets. The cover is then folded upwardly and bent over the rear edge of the cup and the cover lock 22 is inserted through the opening 23.

A cardinal feature of my improved receptacle comprises the cover lock 22. This unique lock comprises a tab which is somewhat wider, in a region intermediate its ends than the cooperating slot, and which tapers gradually toward each end. The inner end is preferably of substantially the same width as the slot and the outer end is preferably considerably narrower than the slot. When shaped in this particular manner the tab is readily inserted through the slot, by virtue of the narrow tapered outer end, and when inserted is tightly held in position by virtue of the tapered inner end wedging in the slot. As the tab is passed through the slot it is flexed to an extent depending upon the excess width of the tab and after passing through the slot the tab straightens out into the position shown in Fig. 2 where it is closely confined. When it is desired to open the receptacle the cover is pulled upwardly and, by virtue of the tapered inner end of the tab, the tab is automatically flexed an amount sufficient to permit it to pass out from the slot. Thus the tab is not only held snugly in locked position when locked but it is automatically flexed by the opposite tapers of the ends both when being inserted and when being withdrawn so that it is only necessary to press the cover and cup together or pull them apart to lock or unlock the cover.

In Figs. 5 and 6 is illustrated a receptacle 24 in which the opening 25 for the cover tab 26 is formed in the front 27 of the box instead of in a folded rim as in Figs. 1 to 4. Moreover, instead of having substantially the same width throughout as in Figs.

1 to 4 the slot 25 in Figs. 5 and 6 is tapered in the same direction as the inner end of the tab. The upper end of the opening has substantially the same width as the corresponding section of the tab, and the tab tapers more rapidly than the opening so that the tab is firmly held in the opening after being inserted thereinto as in Figs. 1 to 4. However, by virtue of the downward flare 10 of the opening the tab need not be flexed so much when passed through the opening as when the opening is of substantially uniform width.

In inserting or withdrawing either the tab 15 22 or the tab 26 the automatic flexing above referred to may be supplemented, if desired, by pressing the opposite sides of the tab together or in other suitable manner.

What I claim is:—

20 1. A receptacle formed of a single piece of sheet material folded into the shape of a rectangular cup comprising front, rear and side portions, gussets between the front and side portions and between the rear and side 25 portions, said gussets being folded along the side portions, an extension on each of said sides having locking tabs folded over and then under the adjacent folded gussets and thereby lock the gussets, front, back and 30 sides in fixed position, rims joining the up-

per edges of said front and back and the gussets adjacent thereto and folding downwardly along the outer sides of said front and back, a cover, a neck joining said cover to the lower edge of said back rim, said front rim having a slot therein, and a tongue on the forward edge of said cover adapted to fit into said slot. 35

2. A blank for paper receptacles comprising a body portion provided with a plurality of fold lines designating a bottom section, front, back and side sections radiating therefrom, gusset corner sections between the said front, back and side sections, a cover portion extending upwardly from the 40 said back section, a longitudinal rim portion extending along the said back section and the adjacent gusset sections, a neck portion connecting the said longitudinal rim section and the cover portion, a longitudinal 45 50 perforated rim portion extending along the said front section and the adjacent gusset sections, and an extension on each side section provided with a neck portion connecting the said extension with an elongate tab 55 parallel thereto.

Signed by me at Boston, Massachusetts, this 13th day of February, 1918.

HAROLD B. CRANSHAW.
